POTATO SACKER

Filed Sept. 27, 1930

UNITED STATES PATENT OFFICE

DAVID E. RATH, OF DUBUQUE, IOWA

POTATO SACKER

Application filed September 27, 1930. Serial No. 484,760.

The present invention pertains to means for putting into paper bags a definite quantity of potatoes and is intended to cure the defects of prior mechanisms designed for this purpose. For example, a mechanism having a tray provided with downwardly extending spouts, in which the tray is turned about a pivot at one side is objectionable for the reason that the spouts tip the bags over and spill the potatoes when the spouts are being removed from the bags. A structure in which the table which supports the bags is lowered away from the potato holding hopper is objectionable for the reason that the hopper must be located at such an elevation that it is difficult to place the bag of potatoes in the hopper and therefore undesirable in use. It is therefore among the objects of my invention to provide a mechanism of the character indicated in which the receiving hopper may be charged with a minimum of labor; to provide a device of the character indicated in which the filling hopper may be removed from the filled bags without danger of spilling them during the operation; to provide an apparatus of the character indicated by means of which a definite quantity of potatoes may be emptied into a hopper and equally divided between a given number of bags so that the amount in each bag will weigh up within a few ounces of the selected amount; to provide an improved mechanism of the character stated; and such further objects, advantages and capabilities as will hereafter appear and as are inherent in the construction disclosed herein. My invention further resides in the combination, construction and arrangement of parts illustrated in the accompanying drawing and, while I have shown therein what is now considered the preferred embodiment of this invention, I desire the same to be understood to be illustrative only and not to be interpreted in a limiting sense.

In the drawing annexed hereto and forming a part thereof, Fig. 1 is an end elevation of a structure embodying my invention; Fig. 2 is a front elevation of the structure shown in Fig. 1; Fig. 3 is a fragmentary vertical section through a portion of this device to illus-

trate certain details of construction; and Fig. 4 is a fragmentary elevation of a portion of this structure showing another detail of construction.

Reference will now be made in greater detail to this construction as illustrated in the accompanying drawing wherein the framework is illustrated as consisting of a plurality of uprights 1 tied together with cross members 2 and having braces 3 in the corners thereof to lend rigidity to the frame. The uprights 1 are formed from angle irons which serve to guide the tray 4 in its movement up and down. This tray is preferably formed of sheet metal pressed into a concave shape as illustrated, or a piece of sheet metal may have its corners cut out and then the sides bent up in the shape indicated, the corners then being secured together in any suitable manner, as by spot welding, riveting, soldering, etc. It is of course understood that the sides of the tray may be of other shapes, as flat, if desired. This hopper has pieces of channel iron 5 extending along its top edges and secured thereto to render the frame rigid. Fig. 3 illustrates one way in which the channel iron may be secured to the edge of the hopper. In this it is illustrated that the edge of the metal is bent outwardly, downwardly, and inwardly around the upper flange of the channel iron 5, thus fastening the two together very securely and rendering the hopper quite rigid.

The bottom of the hopper is provided with any desired number of openings 7 through which extend the upper ends of filling tubes 8, which tubes are secured in place in the openings in any desired manner. In Fig. 3 the diameter of the tubes is illustrated as being somewhat reduced at the ends and then the end of the tube inserted in the opening and bent outwardly to form a flange upon the inside of the hopper 4 to hold the tube in place. These tubes are illustrated as flaring somewhat from the top toward the bottom, the upper diameter being preferably about $5\frac{1}{2}$ inches and the lower diameter about 7 inches. The length of the tubes is then made such and the distance of the bottom end, as illustrated in Figs. 1 and 2, from the floor is

such that these filling tubes will hold just one peck of potatoes. It has been found during my experiments that if the tubes are made of uniform diameter throughout their length or tapered slightly toward the bottom, there will be a bridging effect and the construction will be impractical because of unsatisfactory operation. On the other hand, when these tubes are flared as illustrated no bridging takes place and the potatoes slide down to the bottom and fill up the tubes completely and the tubes may be withdrawn from the bags without danger of part of the potatoes remaining in the filling tubes. In other words, because of the flaring of the tubes the metal will pull away from the potatoes without any trouble whatever. Rubber bands 9 are found very satisfactory to hold the paper bags 10 in place on the filling tubes 8. I have found that short sections of automobile inner tubes of the approximate size make excellent means for holding the upper edges of the bags in place on the filling tubes. In applying the paper bags, I have the hopper 4 in elevated position as illustrated in dotted lines in Fig. 2 and then slip the bags over the tubes and fasten them in place by means of rubber bands as illustrated in Fig. 1. It will be noted that the rubber band is not put all the way around the bag as this is unnecessary to hold the bag from slipping down after it is applied and before the hopper is lowered.

Pairs of cables or chains 11 are connected to each end of the hopper 4 and are connected to similar cables or chains 12 and 13 which pass over pulleys 14 and 15 and then down to a weight 16 to which they are secured. In Fig. 1 it will be noticed that pulley 15 is a double pulley. This is necessitated by virtue of the fact that there are two principal members 12 and 13 which pass over same. Of course one wide pulley would serve the same purpose. To limit the downward movement of the hopper 4 and hold the lower ends of the tube 8 properly spaced from the support upon which the frame work is carried, for example the floor, brackets 17 are secured in the angles and the bottom edges of the channels 5 rest upon these brackets 17 when the hopper is in lowered position. These angles are notched out as indicated at 18 in Fig. 4 and thus they serve as positioning guides to properly position the hopper 4 when in lowered position. The manner of securing these angles in place is immaterial as they may be spot welded, riveted, or secured in any other suitable manner.

A means 19 should be provided for covering any desired number of the filling tubes 8. This means may comprise a plate or plates hinged at the top of one side of the hopper, but I prefer to use covers similar to those used in closing stove pipe openings in chimneys and the like. In Fig. 3 such a cover 19 is illustrated as having a plurality

of fingers 20 which fit into the opening 7 and secure the cover in place thereover.

In the use of this device if a bushel of potatoes is to be sacked in bags which hold one peck each, the bags are mounted upon four of the tubes 8 and the other four tubes are covered so that potatoes will not enter them. This is on the assumption that an apparatus such as illustrated in my drawing is used. It will be understood that a device having more or less than 8 tubes may be used, if desired. I prefer to use the eight tube size because this permits the bagging of two bushels of potatoes at one time. To do this, the bags are placed on all eight of the tubes and fastened in place with the rubber bands 9 and the hopper 4 is then lowered to the full line position. A bag of two bushels or two bags of one bushel each of potatoes is then emptied into the hopper 4 and these run down into the tubes 8. Since these tubes are of just such a size as to hold one peck each, when the hopper 4 is spaced the requisite distance from the floor, the eight tubes will be just level full when the potatoes are all out of the hopper and in the tubes. When they have been so distributed, the weight 16 is pulled down and the hopper and suspended tubes are raised, the rubber first having been released from the bags to permit them to remain upon the floor without dropping. When the hopper is raised, as indicated in dotted outline in Fig. 2, it will be found that there are eight bags of potatoes standing on the floor beneath where the hopper was and each will contain within a few ounces of 15 lbs. These sacks can then be weighed and the weight adjusted by adding or subtracting a potato until substantially the exact amount is found in each bag. It will be understood from the foregoing that if a four tube hopper is used only one bushel of potatoes will be bagged at a time. If a bag contains 100 lbs., which is quite a common weight, instead of 60 or 120 lbs., two of the openings may be covered with plates 19 and then the ten pounds of excess potatoes which do not go into the filling tubes may be removed, after the six tubes are filled. On the other hand, if the user so desires, he may cover one of the openings 7 with the plate 19 and then put 5 lbs. of potatoes from some other bag into the hopper along with the 100 lbs., thus making 105 lbs., which will just fill seven of the tubes. The sacking of potatoes is thus made a quick and easy job by means of this apparatus and a number of bushels of potatoes may be bagged in 15 lb. packages within the space of a few minutes.

Of course it will be understood that the tubes may be made of different sizes, if it is desired to put different quantities of potatoes in the bags. However, the most common size of packages sold at retail is one peck and it is therefore my opinion that this will be sub-

stantially a standard size of tube for use in this machine.

It is of course understood that the specific description of structure set forth above may be departed from without departing from the spirit of my invention as set forth in this specification and the appended claims.

Having now described my invention, I claim:

1. In a potato sacker, a rigid frame, a hopper suspended therein for motion vertically within the frame, means for suspending said hopper to slide vertically in and be guided by said frame, said hopper having openings in the bottom thereof and having filling tubes of definite pre-determined size secured in said openings to receive and sub-divide equally a definite quantity of potatoes put into the hopper.

2. In a potato sacker, a supporting framework having corner posts and a top frame, suspending means supported on the framework for motion relatively thereto, a hopper to which the suspending means is secured, said hopper being held and guided between the corner posts, a counterpoise for the hopper also secured to the suspending means, flared filling tubes secured to the hopper and opening therefrom, said tubes being downwardly directed from the hopper and having their larger ends at the bottom, and means for limiting the downward motion of the hopper and tubes.

3. A structure as defined by claim 2 having elastic bands surrounding the filling tubes for securing thereto bags to be filled.

4. A structure as defined by claim 2 having means for closing the upper ends of any desired number of filling tubes to prevent the potatoes from having access thereto.

5. In a structure of the character described, a rigid openwork frame having angle-shaped upright corner posts, a hopper supported for vertical motion in said frame, means in connection with the corner posts to limit the downward motion of the hopper, suspending means passing upwardly from the hopper and over easily movable supporting means, a counterpoise for the hopper secured to the suspending means, said hopper having openings in the bottom thereof, bag filling tubes of definite predetermined capacity mounted and secured in said openings, said tubes flaring downwardly and adapted to have bags to be filled applied thereto, around the free ends thereof, and means for securing the bags to the tubes.

6. In a structure for the purpose indicated, a substantially rigid upright openwork frame constructed to receive and guide a hopper, means associated with the frame for suspending a hopper therein, said means including a counterpoise and flexible elements connected to the counterpoise and the hopper, a hopper within the frame and slideable substantially

vertically in a rectilinear direction, means for limiting the downward motion of the hopper, said hopper having openings in the bottom thereof, and measuring means secured to the hopper in registry with said openings and adapted to receive commodities to be measured, said commodities passing through the holes in the hopper and into the measuring means, said measuring means being lifted in a rectilinear direction with the hopper when the latter is raised.

7. A structure as defined in claim 6 having means for attaching bags thereto, around the measuring means, to receive the measured commodities from the measuring means.

In witness whereof, I hereunto subscribe my name to this specification.

DAVID E. RATH.
